UNITED STATES PATENT OFFICE.

JESSE FROELICH, OF NEW YORK, N. Y.

DESIGN FOR AN AUTOMOBILE-TIRE.

52,026.

Specification for Design.

Patented May 7, 1918.

Application filed March 16, 1918. Serial No. 222,974. Term of patent 7 years.

To all whom it may concern:

Be it known that I, JESSE FROELICH, a citizen of the United States, residing at No. 215 West 98th street, New York city, in the county of New York and State of New York, have invented a new, original, and ornamental Design for Automobile-Tires, of which the following is a specification, reference being had to the accompanying draw-

ing, forming part thereof, in which there are two figures, one a plan view and another a cross-section of the automobile-tire, showing my new design.

I claim:

The ornamental design for an automobile tire as shown.

JESSE FROELICH.
